Ernest Kohler Inventor

By Mason Fennick Lawrence,
Attorney

UNITED STATES PATENT OFFICE.

ERNEST KOHLER, OF DENVER, COLORADO, ASSIGNOR TO THE UNITED MINES AND MANUFACTURING COMPANY, A CORPORATION OF ARIZONA.

GYRATORY ROUNDAABOUT.

Application filed August 28, 1919. Serial No. 320,393.

To all whom it may concern:

Be it known that I, ERNEST KOHLER, a citizen of the United States, residing at Denver, in the county of Denver and State of Colorado, have invented certain new and useful Improvements in Gyratory Roundabouts; and I do hereby declare the following to be a full, clear, and exact description of the invention, such as will enable others skilled in the art to which it appertains to make and use the same.

This invention relates to an amusement apparatus, and particularly to that type of apparatus involving a rotary passenger carrier organized and constructed to gyrate or move through a peculiar orbit designed to produce mirth and amusement for passengers that are suitably accommodated on the carrier.

It is an object of the present invention to provide a simple, practicable, and inexpensively constructed apparatus, and further to provide an amusement apparatus which requires a minimum number of employees or personal attendants in the operation of the apparatus. Further objects are to provide a device of this kind which will accommodate a considerable number of passengers comfortably; to effect variable gyrations of the passenger carrier; and also to provide an effective organization of brakes and convenient means of ingress and egress for passengers.

With the above and other objects in view, as will be rendered manifest to those versed in the art, the invention consists in the construction, the combination, and in details and arrangements of the parts, as more particularly described hereinafter relative to the embodiment of the invention illustrated in the accompanying drawings, in which;

Fig. 1 is an elevational view of the apparatus, certain of the parts being broken away centrally and vertically to indicate details of construction.

Fig. 2 is a plan view of the apparatus, part of the same being broken away to illustrate arrangement of the parts of the driving mechanism.

In the illustrated embodiment of the invention a passenger carrier 2 is provided, and while here shown as in the form of a plane circular platform, obviously it may be given any other suitable plane configuration. The floor of the carrier 2 is provided with a

circle or other suitable arrangement of seats 3, preferably disposed near the edge of the floor so that the passengers will be carried through a maximum sweep or orbit of movement, and preferably the edge of the carrier 60 or table 2 is provided with a guard or hand-rail 4 and entrance or exit gates at 4' for obvious purposes. To increase the ornamental features of the apparatus, and provide for the accommodation of a musical apparatus, or an orchestra, the center of the carrier is provided with a pagoda 5, under which is represented a mechanical, musical instrument 6, although obviously this may be replaced by an orchestra of suitable 70 pieces.

The carrier 2 is provided with a central downwardly projecting support shown as a shaft or column 7, projecting through a bearing 8 formed in the upper portion of an arch or other suitable support 9, which, in turn, is mounted on a main rotating member such as turn-table 10, supported preferably on anti-friction bearings 11 running on a foundation structure 12, this latter having 80 a bearing 13 to receive the central shaft or trunnion 14 of the turn-table 10. The lower end of the shaft 7, of the passenger-carrying floor or carrier 2, is journaled in an appropriate bearing 7^a on the upper surface 85 of the turn-table 10, so that the turn-table may have rotary motion about its own axis, this carrying the carrier 2 around with it whilst the carrier 2 may have an independent rotary motion which is imparted to it 90 by a suitable drive mechanism applied to the shaft 7. In this case the shaft has on it a worm gear 15 engaging a worm 16 driven by a suitable motor 17, which is mounted on the top of the turn-table 10.

I prefer that the shaft 7 be set with its end eccentrically or crank-like with respect to the axis of the turn-table 10, and in addition to its being so eccentrically set, it is tilted from the vertical so as to hold the floor or carrier 2 at all times at a slightly inclined plane with relation to the horizon.

The turn-table 10 is rotated through means of a motor 20, driving a suitable reduction gear 21, the pinion of which engages 105 a circumferential gear 22 on the periphery of the turn-table.

It will be seen, because of the inclination of the shaft 7 and floor 2, at each rotation of the turn-table 10, the floor will be carried 110

- around in a complete cycle at an inclined plane with respect to the axis of the turn-table, and by virtue of the rotation of the floor or carrier 2 about its own axis, every portion of the periphery of the carrier 2 will be caused to assume different vertical positions between the highest and the lowest position at the sides of the inclined carrier 2.
- 10 The combination of the two movements due to the rotation of the turn-table and to the swinging of the carrier 2 about its axis, produces a very peculiar orbit through which the individual chairs or seats 3, arranged on the carrier 2, are caused to be moved, and this orbit of movement, together with a given rate of movement, will produce the entertaining and mirthful form of amusement apparatus with a high degree of safety.

It is obvious unless the turn-table and platform are caused to stop their rotations so that the entrance and exit 4' will come opposite and on a substantial level with the top of the landing platform 27, ingress and egress from the platform carrier could not be conveniently had. In order, therefore, that the platform carrier may be stopped at the proper position with the entrance 4' opposite the landing platform, I provide independent driving mechanism for the turn-tables and platforms. By this means the turn-table may be conveniently stopped when the eccentric shaft 7 is farthest from the landing platform 27. This will bring the platform carrier at the proper inclination so that one edge of it will be on a level with the landing platform. The operation of the motor 17 will of course be continued until the entrance

and exit gate are brought opposite the landing platform. In order to aid the checking of the rotation of the platform so as to bring it to the desired position and to hold it in that position while passengers are getting on or off of the platform, a shoe 28 is provided, which may be manipulated by the lever 29 by an operator on said platform.

Conductors 31 and collector rings 32 on the perimeter of the turn-table 10, conduct electricity from a source not shown to operate the motor 17.

Having thus described my invention, what I desire to claim is:

1. In an amusement apparatus, a gyratory platform carrier having an axis of rotation inclined fixedly to its axis of revolution and provided with an entrance and exit accommodations for passengers, a landing platform, a holding device thereon adapted to engage the gyratory platform, and means for independently imparting rotary and revolutionary movements to said platform.

2. In an amusement apparatus, a platform carrier provided with an entrance and exit and accommodations for passengers, a turn-table, an inclined support projecting from the turn-table and rotatably supporting the platform carrier in a plane inclined to the plane of rotation of said turn-table, means mounted in a fixed base having transmission devices for rotating the turn-table, and means independent of the turn-table rotating means, and mounted in the turn-table for rotating the platform carrier about its axis.

In testimony whereof I affix my signature.

ERNEST KOHLER.
